Primary Examiner — Cynthia Ramirez(74) *Attorney, Agent, or Firm* — Garrett James O'Sullivan; Eric Brandon Lovell(57) **CLAIM**

The ornamental design for a bending brake assembly set, as shown and described.

DESCRIPTION

FIG. 1 is a side view of a bending brake assembly set; FIG. 2 is a top view of the bending brake assembly set of FIG. 1;

FIG. 3 is a bottom view of the bending brake assembly set of FIG. 1;

FIG. 4 is a side view of a bracket forming part of the bending brake assembly set of FIG. 1;

FIG. 5 is a top view of the bracket forming part of the bending brake assembly set of FIG. 1;

FIG. 6 is a bottom view of the bracket forming part of the bending brake assembly set of FIG. 1;

FIG. 7 is a right side view of the bracket forming part of the bending brake assembly set of FIG. 1; and,

FIG. 8 is a left side view of the bracket forming part of the bending brake assembly set of FIG. 1.

Only the bracket element of the bending brake assembly set is shown in FIGS. 4 through 8 for convenience of illustration.

The bending brake is shown with a symbolic break in its length. The appearance of any portion of the article between the break lines forms no part of the claimed design.
